CLAIM

The ornamental design for a translucent water bottle, as shown and described.

DESCRIPTION

FIG. 1 is a perspective view of a translucent water bottle, showing my new design;

FIG. 2 is a reduced top view thereof;

FIG. 3 is a reduced side elevational thereof; the other side elevations are the same;

FIG. 4 is a greatly enlarged fragmentary cross sectional view taken along the line 4—4 in FIG. 2;

FIG. 5 is a greatly enlarged fragmentary cross sectional view taken along the line 5—5 in FIG. 2;

FIG. 6 is a greatly enlarged fragmentary cross sectional view taken along the line 6—6 in FIG. 2;

FIG. 7 is a greatly enlarged fragmentary cross sectional view taken along the line 7—7 in FIG. 2;

FIG. 8 is a cross sectional view taken along the line 8—8 in FIG. 3;

FIG. 9 is an enlarged fragmentary cross sectional view taken substantially along the line 9—9 in FIG. 2; and,

FIG. 10 is an enlarged fragmentary cross-sectional view taken substantially along the line 10—10 of FIG. 2.
